UNITED STATES PATENT OFFICE.

STUART ELLIS, OF WASHINGTON, DISTRICT OF COLUMBIA.

HOT-WATER RADIATOR.

1,098,238.

Specification of Letters Patent. Patented May 26, 1914.

Application filed April 3, 1913. Serial No. 758,678.

To all whom it may concern:

Be it known that I, STUART ELLIS, a citizen of the United States, residing at Washington, in the District of Columbia, have 5 invented new and useful Improvements in Hot-Water Radiators, of which the following is a specification.

The general object of this invention is to improve upon the hot-water heater shown 10 in the patent to C. M. Wheelock, #882,436, dated March 17, 1908, for an improvement in "hot water heaters."

Specifically, the object is to provide a structure wherein the burner may be held 15 in spaced position with relation to (that is, out of contact with) two of the radiator-sections between which it is placed, so that the air to support combustion, admitted at a point below said burner, may have free 20 access to said burner and pass thereby, on each side thereof.

Objects of improvements, not specifically mentioned, going to make up the ultimate perfection of the device as an entirety, will 25 appear as the specification proceeds, and the nature of the invention more fully appears.

In the accompanying drawings, forming part of my specification, I have illustrated a form of embodiment of my invention 30 capable of carrying out the underlying principles thereof, and in these drawings, in which like reference-characters denote corresponding parts throughout the several views: Figure I is a side elevation of a radiator embodying my improvements; Fig. II is a transverse section on the line 2—2, Fig. I; Fig. III is a horizontal sectional view on the line 3—3, Fig. II, looking in the direction of the arrow thereon; Fig. IV is a 40 fragmentary sectional view of the burner and the two adjacent radiator-sections between which it is disposed, showing the spaced relation of said burner to said radiator-sections.

Referring, now, in detail to the drawings: 45 the numeral 1 represents an ordinary hot-water heater or radiator, which may be supplied with water in the usual or any preferred manner. Between two of the upright sections, as 2 and 3, of the radiator there is preferably disposed a shield 4, the function of which is to confine the heat from the burner (hereinafter to be described). The shield, which is provided with a closed 50 bottom 5, may be held in proper position on the radiator in any suitable manner. The

upper ends 6, 6 of the shield are bent inward and toward each other, so as to engage and bear upon the top of the radiator-sections 2 and 3. The radiator is provided, 60 also, with a gas-igniting aperture 7, normally covered or closed by a sliding door 8, which projects, at its sides, under guiding-strips or tracks 9, 9, carried by the shield 4 and bent inward at their upper ends, as 65 shown at 10, 10, so that, when the door is raised to the limit of its upward movement, there will be sufficient degree of frictional engagement between said door and said track-ends 10, 10 to hold the former against 70 accidental downward movement. The shield 4 is also provided, at a suitable point beneath said aperture 7, with air-inlet holes 11, and, between said holes 11 and said aperture 7, with oppositely-disposed openings 75 12, 12, through which projects a burner 13.

Said burner 13 is provided, in its top, with a longitudinally-disposed series of transversely-extending slits 14. The burner preferably carries, at one end thereof, a 80 flange 15, in this instance integral therewith, and bearing exteriorly against the shield 4. The burner terminates, at its other end, in a screw 16, projecting through a clamping-plate 17 bearing exteriorly against the shield 85 4. The plate 17 and flange 15 are held tightly against the shield 4 by an adjusting-nut 18 threaded on the screw 16. It will be seen, also, that, since the flange 15 and the plate 17 bind tightly against the shield 4 90 when the nut 18 is tightened up, the shield is in turn, caused to bind tightly against and thus be clamped to the radiator-sections 2 and 3. The flange 15, the plate 17, the screw 16, and the nut 18 thus subserve the dual 95 function of holding the burner 13 in position, and, also, of holding the shield 4 in position.

It will be noted that, by the burner-clamping and supporting-means, just described, the 100 burner may be held out of contact with the radiator-sections 2 and 3, so that air from the air-inlet openings 11 may pass freely upward between the sides of said burner 13 and the inner sides of the radiator-sections 2 and 3.

19 is an air-mixer, of any suitable construction, carried by a tube-section 20 carried, in any suitable manner, by the burner 13. The tube-section 20 is preferably curved, 110 as shown, so that the longitudinal axis of the air-mixer 19 lies in a plane parallel with

the shield 4, instead of at right-angles thereto. I have found, in practice, that the elbow of the curved tube-section 20 tends to prevent "flare-backs" of the gas, when 5 lighted initially through the opening 7, as said elbow presents a certain amount of obstruction to the gas.

The radiator 1 is provided with the customary upper and lower horizontal connections 21, 22, respectively, establishing communication between the upright sections 23 of the radiator, as usual. In addition, the radiator is provided, toward the lower end thereof, above the lower series of connections 15 22, preferably at a height of one-third the distance from the bottom of the radiator, with a third series of horizontal connections 24, each of which connects and thus establishes communication with two adjacent vertical radiator-sections, there being no connection 24 between the vertical radiator-sections 2 and 3. The object of this third series of connections 24 is to provide for circulation when the level of the water is below 25 the upper series of connections 21. The radiator 1 is provided, at its upper end, with an exit-tube 25, internally threaded at its outer end. In said threaded end of the tube 25 is disposed a valve-casing 26, carrying a 30 check-valve 28, serving the function of a safety valve.

Having thus fully described my invention, what I claim as new, and desire to secure by Letters Patent of the United States, is:

35 1. The combination with a hot-water radi-

ator or heater, formed of a plurality of parallel, upright sections, of a heat-confining shield disposed between two of said sections, and means for holding said shield in position on the radiator, including: a burner extending between said two sections and having means at one end engaging said shield and a screw-threaded opposite end, a clamping-plate engaging said shield and through which said screw-threaded end projects, and 45 an adjusting-nut carried by said screw-threaded end and engageable with said clamping-plate.

2. The combination with a hot-water radiator or heater, formed of a plurality of parallel, upright sections, of a heat-confining shield disposed between two of said sections, and means for holding said shield in position on the radiator, including: a burner extending between said two sections and 50 spaced therefrom and having means at one end engaging said shield and a screw-threaded opposite end, a clamping-plate engaging said shield and through which said screw-threaded end projects, and an adjusting-nut 55 carried by said screw-threaded end and engageable with said clamping-plate.

In testimony whereof, I have hereunto set my hand in presence of two subscribing witnesses.

STUART ELLIS.
